FUEL FEEDING APPARATUS

Arthur O. Anderson, Davenport, Iowa

Application August 23, 1945, Serial No. 612,289

7 Claims. (Cl. 198—213)

(Granted under the act of March 3, 1883, as
amended April 30, 1928; 370 O. G. 757)

1

The invention described herein may be manufactured and used by or for the Government for governmental purposes, without the payment to me of any royalty thereon.

The present invention relates generally to the art of fuel feeding. More particularly, it provides for an improved attachment for a solid fuel feeding apparatus of a standard heating furnace which comprises means for speedy and easy access to the interior of the feed mechanism housing.

Specifically, the improved attachment includes a hinged interiorly tapered combination coupling and coal chamber adapted to house the feed mechanism of a conventional automatic stoker. The chamber is provided with releasable locking means and may be opened for exposing said feed mechanism through 360° by manual manipulation of the locking means.

In the past in connection with the operation of solid fuel stokers, especially with the under-feed type, it occasionally has been found that a relatively large piece of steel or other hard material has become mixed with coal in the bin or hopper in which it was contained in such a manner that the foreign matter has been fed along with the coal into the feeding tube where it sometimes came in contact with the fuel feeding mechanism and became wedged between the fuel feeding mechanism and the tube housing it, in such a manner as to stop rotation of said fuel feeding mechanism. When this occurs a shear pin normally employed in the fuel feed drive shaft is broken, thereby severing the connection between the prime mover and the drive shaft. In such a contingency, it is usually necessary to shovel all of the coal away from the fuel outlet in the bin, when such a receptacle is used for the fuel, and to employ a lever arm or other tool for manually reversing rotation of the torque screw or other feeding means to disengage the steel or other foreign object. In cases where a hopper is used it is usually necessary to completely unload the hopper in order to gain access to the interior of the housing of the fuel feeding mechanism. After removal of a foreign body a new shear pin may be inserted in the driving shaft, the hopper reloaded and the stoker again placed in operation.

Obviously the above described process is an inefficient and time-consuming repair job. Accordingly, one of the objects of the present invention is the construction of a device providing convenient and speedy access to the fuel feeding mechanism of an automatic stoker for facil-

2

itating repair and/or adjustment necessary to assure smooth and efficient operation of the fuel feeding mechanism.

Another object of my invention is to furnish a sectioned combination coupling and fuel chamber for the conveyor tube of an automatic stoker which may be opened substantially through 360° by manual release of a simple locking means.

A further object of the present invention is the provision of a modified fuel conveyor tube for an automatic stoker adapted to receive a readily removable flanged coupling and fuel chamber.

An additional and important object of my invention is the construction of a coupling for the conveyor tube of an automatic stoker adapted for compression of the fuel into the grooves of the fuel feeding means substantially entirely within the coupling.

A still further object of my invention is the provision of a combination coupling and fuel chamber adapted for installation into existing stoker assemblies with relatively few alterations to the existing plant.

Preferred embodiments of my invention whereby I attain the above and other and further objects are illustrated in the accompanying drawings in which like numerals refer to like parts throughout the several views and wherein:

Fig. 1 is a schematic layout showing one form 30 of arrangement of a solid fuel bin or hopper, a fuel feeding tube, a furnace and the attachment constituting the improvement of the present invention;

Fig. 2 is a perspective view illustrating the 35 means of application of the fuel chamber coupling to the conveyor tube of a stoker and shows one form of locking means used to retain the coupling member in locked relationship relative to said conveyor tube;

Fig. 3 is a side elevation, partly in section, 40 showing the interiorly tapered coupling member and the manner in which it is attached to the conveyor tube of a stoker;

Fig. 4 is an end view of the hinged coupling 45 device in opened position;

Fig. 5 is an end view of the coupling device of Fig. 4 showing the device in closed and locked position;

Fig. 6 is a view of the conveyor and fuel feed 50 tubes of a stoker with the hinged coupling member completely removed;

Fig. 7 is a view similar to Fig. 6 but showing the hinged coupling secured to the fuel feed and conveyor tubes; and

Fig. 8 illustrates an alternative construction

for locking the hinged sections of the coupling chamber.

Referring to Fig. 1, the numeral 1 designates a bin or hopper for solid fuel. A relatively short cylindrical fuel feeding tube 2 is connected to the bin and has secured thereto the improved attachment designated generally by the reference numeral 3 constituting the present invention as hereinafter described. The numeral 4 indicates a conventional furnace. The fuel bin 1 is provided with a generally circular fuel outlet to which is connected the fuel feeding tube 2 as by means of an annular flange member 5 adapted to be secured to the fuel bin 1 by means of any suitable fastening means such as bolts passed through apertures 6 formed in the annular flange member. The attachment 3 comprises a combination coupling and fuel chamber 7 which is adapted to form a connection between the free end of the fuel tube 2 and a fuel conveyor tube 8 and also to house fuel feeding mechanism such as a torque screw or worm 9 (Fig. 2). The conveyor tube 8 is of smaller diameter than the tube 2, for a reason which will hereinafter become apparent.

The member 7, preferably made of cast iron, is generally similar to the hollow frustum of a cone, and is interiorly tapered as at 10 (Fig. 3). The inside diameter of the fuel chamber 7 at the end of the taper 10 adjacent the entrance to the conveyor tube 8 preferably is slightly less than the inside diameter of the latter. With this construction any impediment to continued operation of the feeding means which may be contained in the fuel being fed by the worm 9 will be trapped in the chamber 7 without being passed on to the tube 8 where it would be difficult to retrieve it. The inside surface of the chamber 7 may be either smooth or ribbed. The chamber may consist of two or more substantially identical sections (two in the present instance) indicated by numerals 11 and 12 and hingedly connected as at 13 by means of a pintle 14. Each of these sections is provided with two semi-circular collar elements 15 and 16 positioned at opposite ends of the chamber. These collar elements are grooved on their inner peripheries in the manner indicated at 17 in Fig. 3, which construction adapts them for cooperation with chamfered annular flanges or ribs 18 and 19 formed respectively at one end of the fuel feed tube 2 and the conveyor tube 8 for securing the coupling in position and for preventing axial displacement thereof. As shown most clearly in Figs. 2, 3, and 6 the flange 18 is formed on the end of an adapter member 30 having its other end formed as a sleeve fitting around the outside of the open end of tube 8 and secured thereto by any suitable means such as welding.

Various devices for maintaining the hinged sections 11 and 12 of the chamber 7 in locked relation relative to each other may be employed. Figs. 1-5 and 7 show one form of the locking device and Fig. 8 shows an alternative form which I have chosen to illustrate and describe herein.

The device shown in Figs. 1-5 and 7 comprises a bolt 20 pivotally connected at one end as by means of a pin 21 to a substantially U-shaped dog 22 which may be formed integral with the body portion of the section 11 of the coupling chamber 7. The bolt 20 is threaded at one end and is adapted to receive a complementary interiorly threaded tubular locking member 23 and a washer 31 and to fit into a second substan-

tially U-shaped dog 24 formed integral with the body portion of the other section 12 of the chamber 7. The dogs 22 and 24 may be reinforced in their connections to the collars 15 and 16 respectively as by means of inclined flanges or ribs 25 and 26 as shown in Fig. 2. The two sections 11 and 12 of the coupling chamber 7 are adapted to be releasably locked by manipulation of a handle 27 positioned adjacent one end of the locking member 23 and extending therethrough, the locking member being adapted for projection against the washer 31 by the cooperation of its interiorly threaded portion with the threaded part of the bolt 20.

The coupling chamber 7 may be further secured against rotation relative to the ribs 18 and 19 by means of a pair of dowel pins 28 adapted to pin the collars 15 and 16 respectively to the annular flanges 18 and 19 by means of a slot in each of the latter, as shown at 29 in Fig. 2. The pin 28 is preferably made of soft steel and may be inserted at any convenient point to secure the desired result. This pin is preferably substantially equal in strength to the shear pin usually employed in stokers to break the connection between the prime mover and the fuel feed drive shaft in emergencies which may arise through malfunctioning of the fuel feeding mechanism through failure of the screw or worm carrying shaft to rotate due to an obstruction in the fuel to be fed or otherwise, as is well understood in the art. It will be evident that by reason of the tapering of the chamber solid fuel fed into the interior thereof will be compressed into the spiral grooves of the feed screw 9 substantially entirely within the chamber. Consequently if there is any foreign object mixed with the fuel it will be engaged, if at all, between the feed screw and its surrounding enclosure at some point within the feeding chamber. Thus should it be necessary to remove any obstruction affecting smooth continuous operation of the fuel feeding screw it can be easily and quickly accomplished by releasing the locking bolt 20, disengaging it from the dogs 22 and 24 and removing the hinged chamber 7 entirely as shown in Fig. 6.

Fig. 8 shows a modified form of attachment designated by the numeral 7a and having all the characteristics of the attachment 7 except that two locking bolts and four dogs are employed. Corresponding similar parts are designated by corresponding reference characters to which the exponent "a" has been added.

As previously mentioned one of the important features of my invention resides in the ease and simplicity with which it may be incorporated into known types of fuel feeding assemblies with but slight modifications to the existing plant. For example, a typical installation prior to modification to incorporate my improved coupling will be arranged in such manner that the tube 8 is constructed as a continuous single member having enlarged flange means secured to its end adapted for fastening directly to the hopper 1. It is accordingly only necessary in such cases to remove the enlarged flange and substitute my double flanged cylindrical member 2 therefor, sever a short section from the tube 8, and secure the adapter flange 30 in place on the severed end of tube 8. The assembly will then be in the condition illustrated in Fig. 6 in readiness to receive my improved coupling device 3 which may then be fitted over the flanges 18 and 19 and securely but releasably locked in place by the bolt 20 and shear pins 28. As there

are many known types of stoker assemblies the details may vary slightly according to the different modifications encountered but in each case the alterations necessary will be of a relatively minor character and extent.

Although I have illustrated and described herein only preferred embodiments of my coupling chamber, it is obvious that others of many types and variably positioned, could be used depending upon the length of the fuel feed tube and of the conveyor tube. Also my invention is adapted among other things for use in overfeed, underfeed and central feed stokers and it is not therefore my intention to be limited to the underfeed type illustrated.

Many alterations and modifications of the present invention will no doubt occur to those skilled in the art and I do not therefore desire to be restricted by the precise disclosure made herein. Accordingly it is my intention to be limited only by the prior art and the appended claims.

I claim:

1. In a stoker for feeding solid fuel from a fuel source to a furnace, a fuel inlet tube, means for connecting one end of said fuel inlet tube to said fuel source, an annular rib on the other end of said fuel inlet tube, a fuel conveyor tube, one end of which is adapted to be connected to a furnace, an annular rib on the other end of said conveyor tube, said ribbed ends of said inlet and conveyor tubes being coaxially spaced apart, fuel-feeding mechanism housed by said tubes but exposed at the spaced apart ribbed ends of said tubes, an interiorly tapered fuel chamber interposed between the ribbed ends of said inlet and conveyor tubes and having first and second separable sections, said fuel chamber being adapted to house that portion of said fuel-feeding mechanism between the ribbed ends of said tubes and to compress fuel between the walls of said chamber and said fuel-feeding mechanism substantially entirely within said chamber, means for hingedly connecting said sections whereby they may be opened and closed through 360° about the aforesaid portion of said fuel-feeding mechanism, keeper means on each of said sections, releasable latch means cooperable with said keeper means for releasably locking said sections in closed position, a pair of complementary collar elements at each end of said fuel chamber sections, means forming a groove on the interior of each of said collar elements, each pair of said collar elements being adapted respectively to encircle the ribbed ends of said tubes with said grooves embracing said ribs for substantially preventing axial displacement of said fuel chamber sections relative to said tubes, and means for confining said fuel chamber against rotation relative to said tubes.

2. In a stoker for feeding solid fuel from a fuel source to a furnace, a fuel inlet tube, means for connecting one end of said fuel inlet tube to said fuel source, an annular rib on the other end of said fuel inlet tube, a fuel conveyor tube, one end of which is adapted to be connected to a furnace, an annular rib on the other end of said conveyor tube, said ribbed ends of said inlet and conveyor tubes being coaxially spaced apart, fuel-feeding mechanism housed by said tubes but exposed at the spaced apart ribbed ends of said tubes, an interiorly tapered fuel chamber interposed between the ribbed ends of said tubes and having first and second separable sections, said fuel chamber being adapted to house that portion

of said fuel-feeding mechanism between the ribbed ends of said tubes and to compress fuel between the walls of said chamber and said fuel-feeding mechanism substantially entirely within said chamber, means for hingedly connecting said sections whereby they may be opened and closed through 360° about the aforesaid portion of said fuel-feeding mechanism, releasable latch means for releasably locking said sections in closed position, a pair of complementary collar elements at each end of said fuel chamber sections, means forming a groove on the interior of each said collar elements, each pair of said collar elements being adapted respectively to encircle the ribbed ends of said tubes with said grooves embracing said ribs for substantially preventing axial displacement of said fuel chamber sections relative to said tubes, and means for confining said fuel chamber against rotation relative to said tubes.

3. In a stoker for feeding solid fuel from a fuel source to a furnace, a fuel inlet tube, means for connecting one end of said fuel inlet tube to said fuel source, an annular rib on the other end of said fuel inlet tube, a fuel conveyor tube, one end of which is adapted to be connected to a furnace, an annular rib on the other end of said conveyor tube, said ribbed ends of said inlet and conveyor tubes being coaxially spaced apart, fuel-feeding mechanism housed by said tubes but exposed at the spaced apart ribbed ends of said tubes, an interiorly tapered fuel chamber interposed between the ribbed ends of said tubes, said fuel chamber being adapted to house that portion of said fuel-feeding mechanism between the ribbed ends of said tubes and to compress fuel between the walls of said chamber and said fuel-feeding mechanism substantially entirely within said chamber, means providing for interior access to said chamber to expose a portion of said fuel-feeding mechanism between the ribbed ends of said tubes, a pair of collar elements respectively at opposite ends of said fuel chamber, means forming a groove on the interior of each of said collar elements, said collar elements being adapted respectively to encircle the ribbed ends of said tubes with said grooves embracing said ribs for substantially preventing axial displacement of said fuel chamber sections relative to said tubes, and means for confining said fuel chamber against rotation relative to said tubes.

4. An attachment for a stoker adapted to be releasably secured to a fuel conveyor tube of said stoker, said attachment constituting a housing for a portion of the fuel feeding mechanism of the stoker and comprising a fuel chamber having first and second separable sections, means for substantially preventing axial displacement of said sections relative to said fuel conveyor tube, means for hingedly connecting said sections whereby they may be opened and closed relative to each other for exposing a portion of said fuel feeding mechanism through 360°, keeper means on each of said sections and latch means cooperable with said keeper means for releasably locking said sections relative to each other.

5. An appliance for an automatic stoker adapted to feed fuel to a furnace from a fuel source by means of fuel feeding mechanism housed in a conveyor tube, said appliance constituting a housing for a portion of the fuel feeding mechanism and comprising an interiorly tapered fuel chamber, means for connecting one end of said chamber to said conveyor tube and coaxially therewith, means for connecting the other end of 75 said chamber to a fuel inlet tube, said chamber

being adapted to compress fuel between the walls thereof and the fuel conveyor means substantially entirely within said chamber, and means for disconnecting said fuel chamber from the conveyor tube and the fuel inlet tube for exposing the aforesaid chamber housed portion of the fuel feeding mechanism through 360°.

6. In combination, in a stoker for feeding solid fuel from a fuel source to a furnace and having fuel feeding mechanism, an interiorly tapered fuel chamber having means for access to the interior thereof and adapted to house a portion of said fuel feeding mechanism, means for connecting said fuel chamber to said fuel source, means for connecting said fuel chamber to said furnace, said tapered chamber being adapted to compress

fuel fed therethrough between the walls thereof and the fuel feeding means substantially entirely within said chamber.

7. A device for a stoker adapted to be releasably secured at one end to a fuel conveyor tube in said stoker, and at its other end to a fuel inlet tube from a fuel source, said device constituting a housing for a portion of the fuel feed mechanism of said stoker and comprising a tapered fuel chamber having at least two sections adapted to be opened and closed relative to each other, and means including the aforesaid sections for disconnecting said fuel chamber from said conveyor tube and said fuel inlet tube for exposing said fuel feeding mechanism through 360°.

ARTHUR O. ANDERSON.
